The present invention relates to logic circuits which are useful in data processing equipment. More particularly, the invention relates to unipolar transistor circuits for performing logical inversion or transformation.

In unipolar transistor logic circuits the voltages representing binary digits have different signs at the input and output circuits to the transistor. For example, for a P-type transistor, a binary "one" input may be represented by a voltage $+W_o/3$ and a binary "zero" input by a voltage $+W_o$. The corresponding output voltages from the circuit are $-W_o/3$ for binary "one" and $-W_o$ for binary "zero."

Logical inversion requires that a voltage $-W_o$ be converted to a voltage $+W_o/3$ and a voltage $-W_o/3$ to a voltage $+W_o$. The circuits of the present invention perform this function. In addition, these circuits are simple in that they employ few elements. Moreover, they can be integrated into one stick of semiconductor material. One of the circuits to be discussed has the further advantage that it can be made of the same type of semiconductor material as the preceding and succeeding logic stages. Accordingly, if appropriately topologically arranged, this inverter can be integrated into the same stick of material as the remaining logic circuits.

The inverters of the invention include an input terminal for receiving an input voltage at one of two levels, one representing the binary digit "one" and the other the binary digit "zero." A circuit which includes a unipolar transistor through which a constant current flows is connected at one electrode to said input terminal. An output terminal is connected to a second electrode of the unipolar transistor and it provides output voltages at two levels which are different than the levels of the input terminal. One of these output voltage levels represents the binary digit "zero" when the voltage at the input terminal represents the binary digit "one" and the other of these levels represents the binary digit "one" when the voltage at the input terminal represents the binary digit "zero."

The invention is described in greater detail below and is illustrated in the following drawing of which:

FIG. 1 is a schematic showing of a unipolar transistor;

FIGS. 2, 3 and 4 are schematic circuit diagrams to help explain the operation of the unipolar transistor;

FIG. 5 is a family of characteristic curves of drain current versus drain voltage for a particular unipolar transistor;

FIG. 6 is a family of characteristic curves of drain current versus source voltage for a particular unipolar transistor;

FIG. 7 is a schematic circuit diagram of an "and" circuit, followed by an inverter according to the present invention, followed by an "or" circuit;

FIGS. 10 and 11 are schematic circuit diagrams of still other inverter circuits according to the present invention.

The circuits of the present invention are made up of unipolar transistors, some acting as active elements and some acting as passive elements such as resistors. Such transistors are described in an article by Wallmark and Marcus appearing in the IRE Transactions on Electronic Computers, June 1959, page 98 and elsewhere in the liter-

ature. A brief description is given below of the element and certain characteristics of its operation which are important in the present invention.

The unipolar transistor is shown schematically in FIG. 1. The particular one shown includes a P-type region 10 and an N-type region 12 with a PN junction 14 between the two regions. Charge carriers (electrons in the present case) flow from the source electrode 16 through the N-type material of the region 12 to the drain electrode 18. The N-type material includes a portion 20 of restricted cross-section known as the "channel." A gate electrode 22 is connected to the P-type region 10. Voltages applied to the gate electrode 22 change the effective cross-section of the channel 20 thereby altering its impedance and controlling the current flow from the source 16 to the drain 18. For example, in the transistor illustrated, as the voltage $-V_g$ on the gate electrode 22 is made more negative, the drain current flow decreases.

An important parameter in the operation of a unipolar transistor is its pinch-off voltage P_o . The pinch-off voltage may be determined in the following manner. The source and drain electrodes are connected together as shown in FIG. 2. An adjustable voltage source shown as a battery 24 is then connected between this common connection 26 and the gate electrode 28 in a sense to reverse bias the gate electrode. As the reverse bias voltage on the gate electrode is increased, the PN junction depletion region moves into the channel as illustrated in FIG. 2 thereby decreasing the effective channel cross-section. As the reverse bias voltage is increased still further, the depletion region moves further across the channel until finally it completely closes off the channel as shown in FIG. 3. The voltage at which the channel just closes off is defined as P_o , the pinch-off voltage.

In general, a unipolar transistor is operated with a voltage V_{dd} between the source and drain electrodes as is shown in FIG. 4. This voltage establishes a current in the channel between the source and drain electrodes and it is this current which is modulated by the depletion region depth and hence by the gate voltage V_{gg} .

In the showing of FIG. 4, the source voltage V_s is chosen as the reference and accordingly the source electrode is connected to ground. A voltage source, shown as battery 30, is connected between the source and drain electrodes with its positive terminal connected to the drain electrode. This produces a flow of electrons from the source to the drain. A biasing voltage source, shown as battery 32, is connected between the source and gate electrodes.

As can be seen in FIG. 4, the depletion region is greater at the drain end of the transistor than at the source end. This is because the gate-to-drain voltage $V_g + V_d$ is greater than the gate-to-source voltage V_g and the extent of the depletion region varies along the length of the channel in accordance with the IR voltage drop along the channel.

At some value of gate voltage, the gate-to-drain voltage $V_g + V_d$ will equal the pinch-off voltage P_o . At that point, the depth of depletion region causes the channel to pinch-off but only at the drain end of the channel. Although this would seem to indicate that the drain current must immediately go to zero, it has been found that this is not the case; in fact, the current levels off and remains at a constant value essentially independent of any further increase in drain voltage. In other words, the transistor may be said to be at saturation under these conditions. The reason, at least quantitatively, for this phenomenon is not completely known.

The family of curves of FIG. 5 illustrates what is explained above. It may be seen from FIG. 5 that as the drain voltage is increased, the drain current increases until the gate voltage minus the drain voltage is equal to the

pinch-off voltage P_o . Thereafter, the drain current remains substantially constant. For example, as may be seen from the lower curve legended $V_g = +2P_o/3$, when V_d equals $-P_o/3$, the drain current I_d becomes constant. At that point $V_g - V_d = P_o$, the pinch-off voltage.

The current flow through a unipolar transistor stops when the gate-to-source voltage reaches the pinch-off value thereby closing off the source end of the channel as well as the previously closed drain end of the channel. This is not shown explicitly in FIG. 5 but it may be observed that as V_g approaches P_o , that is, as $V_g - V_s$ approaches P_o , the drain current gets smaller and smaller.

To summarize the above, when the gate voltage minus the drain voltage ($V_g - V_d$) is equal to or greater than the pinch-off voltage P_o , the current flowing through unipolar transistor is constant. It is further seen from FIG. 5 that the amount of constant current flowing under these conditions depends on the gate-to-source voltage $V_g - V_d$. Further, all current flow through unipolar transistor may be cut-off when both ends of the channel close off, that is, when $V_g - V_s$ is also equal to or greater than P_o .

FIG. 6, which is a plot of source voltage V_s versus drain current I_d for different values of gate voltage V_g , also illustrates an interesting characteristic of unipolar transistors. The circuit whose characters are plotted is shown above the curves. It may be seen from the curves that equal increments of gate voltage at a given current correspond to equal increments of source voltage. (This has been found to be the case only when the drain voltage is sufficiently high—higher than P_o .) For example, if the current is maintained constant at 0.4 milliamper, as indicated by dashed line 32, then a change in gate voltage from +15 to +10 volts corresponds to a change in source voltage from -5 volts to -10 volts. A further change in gate voltage from +10 volts to +5 volts results in a corresponding change in source voltage from -10 volts to -15 volts. This phenomenon is made use of in the circuit of the invention shown in FIG. 7.

In the circuits which follow, the following convention is adopted. The symbols V_d , V_g and V_s refer to the drain, gate and source voltages. A unipolar transistor in which the channel region is of a P-type is shown cross-hatched. A unipolar transistor in which the channel is of N-type is shown in the clear. These transistors are referred to as P- and N-type transistors, respectively. Also, as implied in the introduction, a binary "zero" at the input to an N-type transistor is a voltage of value $-W_o$ and a binary "one" input to the same transistor is a voltage of value $-W_o/3$. A binary "one" output of an N-type transistor is a voltage $+W_o/3$ and a binary "zero" output is a voltage $+W_o$. A binary "one" input to a P-type transistor is a voltage $+W_o/3$ and a binary "zero" input to the same transistor is a voltage $+W_o$. A binary "one" output of a P-type transistor is a voltage $-W_o/3$ and a binary "zero" output of the same transistor is a voltage $-W_o$.

A conventional pinch-off voltage to employ with unipolar transistor circuits is W_o , where $W_o = 15$ volts. (The pinch-off voltage for a unipolar transistor is a function of its channel depth and is designed into the transistor in the manufacturing process.) One such circuit is shown to the left of FIG. 7. It consists of two N-type unipolar transistors 34 and 36 connected in series source-to-drain. A resistor, which may be a unipolar transistor element the gate of which is connected to the source, is shown at 38. These three elements comprise an "and" circuit. When a binary "one" input $-W_o/3$ is simultaneously applied to both transistors, they both conduct and a binary "one" output $+W_o/3$ appears at source electrode 40. If either one of the transistors 34, 36 receive a binary "zero" output, no conduction occurs through transistors 34 and 36, and $+W_o$ corresponding to binary "zero" appears at the output terminal.

One form of logical inverter according to the present invention is shown in the dashed block 42 following the

10 "and" gate just described. This circuit includes a P-type unipolar transistor 44 connected in series with a constant current source 46. The transistor is chosen to have a pinch-off voltage $P_o = 2W_o$. The drain electrode 48 is maintained at a sufficiently high negative voltage that the gate-to-drain voltage $V_g - V_d$ is always greater than the pinch-off voltage P_o . Under these conditions, the transistor 44 operates at saturation, that is, in its constant current region, as already discussed.

15 It has already been mentioned that the gate voltage V_g assumes one of the two values $+W_o$ and $+W_o/3$. Accordingly, the drain voltage may arbitrarily be selected to be $-8/3 W_o$, for example. Under these circumstances, the gate-to-drain voltage is either $11/3 W_o$ or $3W_o$. The pinch-off voltage P_o for transistor 44 is $2W_o$ and it is therefore seen that the gate-to-drain voltage is always greater than this.

20 If the current passing through transistor 44 is constant, and the drain voltage is sufficiently high, then a given change in gate voltage corresponds to the same change in source voltage. This may be seen in FIG. 6. The constant current passing through transistor 44 determines the actual value of the source voltage. For example, as can be seen from FIG. 6, dashed line 50, if the 25 current passing through the transistor is 0.5 milliamper, when $V_g = +15$ volts, $V_s = -3$ volts; when $V_g = +5$ volts, $V_s = -13$ volts. The difference between these output voltages is equal to the difference between the binary digits "one" and "zero" but the absolute values of the 30 voltages do not correspond to the binary digits "one" and "zero," respectively. It is therefore necessary to adjust the source 46 to provide a value of current such that V_s assumes the desired values $-W_o/3$ (-5 volts) and $-W_o$ (-15 volts) in response to gate inputs $+W_o$ and $+W_o/3$, respectively. As can be seen from FIG. 6, this 35 value of current is 0.4 of a milliamper.

40 One particularly advantageous way of achieving a constant current source for the inverter of the invention is shown in FIG. 8. Corresponding reference characters have been applied to corresponding elements in the circuits of FIGS. 7 and 8. The constant current source 46 includes a unipolar transistor 52. As already mentioned, it is desired that the output voltage V_{out} (legended V_s in FIG. 7) vary between values $-W_o/3$ and $-W_o$. 45 This output voltage is the same as the drain voltage V_d for transistor 52. In order to have transistor 52 provide a constant current, its source-to-gate voltage is made greater than the pinch-off voltage. The pinch-off voltage for transistor 52 is $2W_o$, the same as the pinch-off voltage for transistor 44. Accordingly, one may arbitrarily choose some fixed voltage for the gate electrode 54 of transistor 52, such as $+8/3 W_o$, such that $V_g - V_d$ for transistor 52 is always greater than $2W_o$.

50 With the two parameters V_d and V_g for transistor 52 chosen as above, transistor 52 conducts a constant current. V_s , the source voltage of transistor 52, is now fixed at a value such that: (a) the source-to-gate voltage for transistor 52 is less than its pinch-off voltage (this permits transistor 52 to conduct); and (b) the magnitude of the current conducted by transistor 52 is the desired one, namely 0.4 of a milliamper. It can be seen from FIG. 5 that when the source-to-gate voltage is $2P_o/3$, then the current conducted is, in fact, 0.4 milliamper. Since V_g has been preset to $8/3 W_o$ the source voltage for transistor 52 is made to be $4/3 W_o$, so that the source to 55 gate voltage $V_g - V_s$ is in fact $2P_o/3$

$$(8/3 W_o - 4/3 W_o = 4/3 W_o = 2P_o/3)$$

60 Returning for a moment to FIG. 7, the inverter 42 is shown connected to an "or" gate. The gate is not part of the present invention but is illustrated to show one place in which the inverter may be used. The gate consists of two N-type unipolar transistors 56 and 58 connected in parallel. If either one or both of the transistors 56 and 58 is conducting, the output voltage

available at terminals 60 is $W_o/3$. If both transistors are cut-off, the output voltage available is $+W_o$. One input to the "or" gate is the V_s output of transistor 44; the second input is a voltage V_{g3} from another stage, not shown.

It may be observed that the inverter of the present invention, which is made of P-type transistors, is connected between two logic stages made of N-type transistors. It is to be understood, of course, that the inverter can be made of N-type transistors provided appropriate power supplies are employed. In this case, the logic stages at input and output may be made of P-type transistors.

The circuit of FIG. 9 is the same as the one of FIG. 8 but is in integrated form. In other words, the two transistors are formed of a single "stick" of semiconductor material. The source electrode of transistor 54 is common with the drain electrode of transistor 52. The two transistors are effectively isolated from one another with respect to transistor action by the slot 62.

One important advantage of the inverter circuits shown in FIGS. 7 to 9 is that they provide a constant, direct current level shift over a wide range of voltage input and hence provide for exact logical inversion. Furthermore, the absolute values of the output voltages obtained with the inverter can easily be varied by changing the bias provided by the constant current source unipolar transistor. Hence, inversion for signals at levels other than W_o and $W_o/3$ may be attained simply. Further, as is shown in FIG. 9, the two unipolar transistors are substantially identical and can be fabricated from a single stick.

The circuits of FIGS. 7-9 have one disadvantage, namely that they must be fabricated from a material different than the material of the logic stages preceding and following the inverter. As shown in FIG. 7, the transistors of the logic stages are of N-type whereas the transistor of the inverter is P-type. This means that the inverter cannot easily be fabricated into the same stick of material as, for example, the "and" and "or" gates shown.

The circuit of FIG. 10 overcomes the disadvantage above. The circuit consists of two resistors 64 and 66 and a unipolar transistor 68. The three elements are connected in series with resistor 64 connected to the drain electrode 70 and resistor 66 connected to the source electrode 72. The input voltage V_{in} is applied to terminal 73 of the resistor and the output voltage V_{out} is taken from the drain electrode 70.

The input voltage comes from a previous logic stage and may be either $+W_o/3$ or $+W_o$ corresponding to binary "one" and binary "zero," respectively. As already mentioned, such voltages are obtained at the output of N-type unipolar transistors. Transistor 68 is also of N-type. The output voltage desired is $-W_o$ or $-W_o/3$ and these voltages are appropriate for application to following N-type unipolar transistor logic stage (not shown).

In order to obtain the same voltage increment at the output as between voltages $+W_o/3$ and $+W_o$ at the input, the current through transistor 68 is maintained constant. This is achieved by maintaining the gate voltage V_g at a value such that the gate-to-drain voltage always exceeds the pinch-off voltage. The pinch-off voltage for transistor 68 is chosen to be W_o . The output voltage desired is $-W_o$ or $-W_o/3$. Accordingly, the gate voltage may arbitrarily be chosen at any negative value equal to or greater in magnitude than $-2W_o$. For the sake of illustration, the value $-2W_o$ is chosen.

The constant current through the transistor 68 is then selected, typically at a value of one-half the maximum possible current. This maximum current corresponds to a gate-to-source voltage of "zero." Resistor 64 is then chosen so that for the given constant current, the voltage across resistor 64 is the desired value for prop-

er inversion of the input signal. For the input signal levels $-W_o$ and $-W_o/3$, this desired voltage is $+4/3 W_o$, yielding an output of $+W_o/3$ and $+W_o$, respectively. V_b may arbitrarily be chosen at some value substantially greater than several times the pinch-off voltage such as $-5W_o$. Resistor 66 is then chosen so that V_s is of the proper value to yield the desired constant current. The design of the circuit above is such that typical variations in the parameters of transistor 68 are only slightly reflected in variations of the inversion voltage across resistor 64. One reason is the relatively large value of resistor 66. Further, the circuit possesses a high degree of self-compensation in that a change in current or voltage V_b is compensated by a change in voltage V_s in a sense to tend to maintain the current at its former value and V_d constant. These are desirable features in assuring reliability of circuit operation. A further advantage of this type of inverter is that it is fabricated from elements identical to those used in the previous logic circuits, and hence may be incorporated into the same stick of semiconductor material. For example, the input to the circuit may be the output of AND gate 38, 34, 36. This is the same AND gate as is illustrated in FIG. 7 and an explanation of its operations appears in the discussion of FIG. 7.

Employing the values of voltage noted on FIG. 10, and assuming W_o to be 15 volts, a suitable circuit according to FIG. 10 may be designed as follows:

A current is chosen which the transistor can conduct and which is otherwise suitable for the circuit design. The current, for example, may be 0.2 milliamperes. From FIG. 10 it is seen that:

$$R_{64} = \frac{E_{64}}{I} \quad (1)$$

Substituting numbers and solving:

$$R_{64} = \frac{W_o/3 - (-W_o)}{I} = 10,000 \text{ ohms}$$

It is also seen from FIG. 10 that:

$$IR_{66} = V_b - V_s \quad (2)$$

and

$$IR_{64} = 4/3 W_o \quad (3)$$

Dividing 2 by 3 and substituting gives:

$$\frac{R_{66}}{R_{64}} = \frac{|-5W_o - V_s|}{|4/3W_o|} \quad (4)$$

The value of V_s must fall within $-2W_o$ and $-W_o$ to permit transistor 68 to conduct. Assume the value $-3W_o/2$. Substituting in 4 and solving for R_{66} gives:

$$\frac{R_{66}}{R_{64}} = \frac{|-5W_o + 3W_o/2|}{4/3W_o}$$

$$R_{66} = 65,000 \text{ ohms}$$

The circuit of FIG. 11 is the circuit of FIG. 10 in integrated form. Similar reference numerals have been applied to similar elements. Note that resistors 66 and 64 are unipolar transistors with no connection to the respective gate electrodes of these transistors. The value of the resistance depends in each case upon the length of the channel region and can be made any practical value desired during the manufacturing process.
